UNITED STATES PATENT OFFICE.

EDGAR L. ZIEGLER, OF JACKSON, MISSISSIPPI.

MACHINE FOR CUTTING WINDOW-STILES.

No. 916,520.

Specification of Letters Patent. Patented March 30, 1909.

Application filed February 8, 1908. Serial No. 414,946.

To all whom it may concern:

Be it known that I, EDGAR L. ZIEGLER, a citizen of the United States, residing at Jackson, in the county of Hinds and State of Mississippi, have invented a new and useful Improvement in Machines for Cutting Window-Stiles, of which the following is a specification.

This invention relates to a machine for cutting pockets in pulley stiles. While these pockets have been heretofore cut by machines but only one stile is operated upon at any time and the object of this invention is to double the capacity of the machine by 15 constructing a device of this kind which will operate simultaneously and upon a pair of pulley stiles and a further object of the invention is a machine of this kind which can be set to cut pockets of various lengths.

20 The invention consists of a rotatable shaft carrying two circular saws one above the other, and the reciprocating shafts carrying cross saws, together with means for holding in position pulley stiles upon opposite sides 25 of the circular saws when in position to be operated upon both sides by the cross saw.

In the drawings forming part of this specification:—Figure 1 is a plan view of my machine. Fig. 2 is a side view. Fig. 3 is a 30 partial longitudinal section taken through the frame supporting the cutting device, on the line 3—3 of Fig. 1. Fig. 4 is a section on the line 4—4 of Fig. 2. Fig. 5 is a detail sectional view showing the manner of mounting the circular saws. Fig. 6 is a detail sectional view showing the manner of holding the inner cross saws.

In these drawings A represents the table of frame upon which the mechanism is 40 mounted and upon which are two adjustable plates A' centrally cut out as shown at A² and set upright parallel to each other. Along the outer sides of these plates are rods B, which extend in advance of the plates and 45 are held to them by suitable staples. Links B' are pivoted at their outer end to the rear corner portions of a movable rectangular frame C which rests upon the supporting table of frame A. To a front corner of the 50 frame C is pivotally connected a lever D which is slotted as shown at D' and is provided with a handle D² and a spring pressed hand grip D³ which grip is also provided with a projecting shoulder D⁴ between its gripping end and its pivotal point. A link D⁵ is piv-

totally connected to the other forward end of the frame C and is provided with a suitable pin D⁶ which engages the slot D' and slides therein. The forward ends of the rods B are pivotally connected respectively to the lever 60 D and to the link D⁵ and it will be obvious that the shifting of the handle D² will spread the rods B or draw them closer together, according to direction of the movement of the handle, thus bringing the plates A' the 65 desired distance apart.

A vertical shaft E is mounted in the frame and is provided on its lower portion with a drum E', which is driven by a belt E² from a drive pulley E³ mounted on a shaft E⁴ carried in suitable bearings at the rear end of the table A. The shaft E⁴ can be driven by any suitable means and I have shown a handle E⁵ to be used where the device is hand operated. In Fig. 5 I have shown a detail 70 enlarged view of the upper portion of the shaft E from which it will be seen that this portion is threaded and sleeves E⁶ inclose the greater portion of this threaded part being held in place by suitable nuts E⁷. These 75 sleeves serve to support and space two circular saws E⁸ one above the other. This portion of the shaft E extends upwardly between the plates A', the saws E⁸ being in proper position to cut with the grain the two 80 long cuts in forming the pulley stile pockets. 85

To make the cross-cuts at each end of the long cuts the following mechanism is provided: A shaft F is hung in fixed bearings and a shaft F' is hung in movable bearings 90 F². These bearings are moved longitudinally along the frame A by means of a threaded rod F³ operated by a suitable hand wheel F⁴ at the front of the machine. The shaft F is provided with a pulley G, over 95 which runs a belt G' which also runs over a pulley G² fixed upon the shaft E⁴. Rotation of the shaft F is conveyed to shaft F' by a train of link gears H, thereby permitting adjustment of the shaft F' with respect to the 100 shaft F without throwing the gears of the train out of mesh with each other. Each of the shafts F and F' carry three upwardly extending reciprocating arms J. These arms are pivotally connected to plates J' which are 105 mounted upon eccentrics J² mounted in turn upon the said shafts. At their upper ends the four outer arms J carry clamps J³ in which are held cross-cut saws J⁴. The two inner arms J which extend upwardly be- 110

tween the plates A carry each two cross-cut saws J⁵, held in a single clamp, which clamp is shown in detail in Fig. 6 and consists of a flanged U-shaped piece of metal J⁶ fitted upon 5 one of the inner arms J and having a set screw J⁷ working through its bow portion and a plate J⁸ bolted to the flanges, the saws being held between said plate and the said flanges. The clamp is locked to the arm J, by a wedge 10 J⁹ upon which the set screw J⁷ bears.

A shaft K is journaled in the frame A and carries a gear wheel K' which meshes with a rack bar K² formed on the under side of a side member of the frame C and by turning 15 the crank handle K³ connected to one end of the shaft K the frame C and all parts connected thereto including the plates A' travel longitudinally upon the frame or table A. To clamp the pulley stiles in position levers 20 L are pivoted at their inner ends in depending brackets L' and their forward end portions engage suitable stepped rack bars L² carried by the forward end portions of the plates A'. Rods L³ pass vertically and loosely through 25 the plates A' and have upper threaded portions upon which are mounted inwardly extending plates L locked in the proper horizontal plane by means of nuts placed upon each side of said plates L⁴. These plates 30 project over the pulley stile M to be operated upon and carry spring plates L⁵ which bear upon the upper edges of the stiles and clamp them in position. Each rod is also provided with a coil spring L⁶ arranged between 35 the plate A' through which the rod passes and the plate L⁴ supporting the spring L⁵. It will be obvious that as the levers L are thrown downwardly at their forward ends they will draw down the rods L³ bringing the 40 spring plates L⁵ into binding contact with the pulley stiles M. These clamp the stiles against any vertical movement and rear movement is effectively prevented by means of stops N. Spring clips O are also carried 45 by the inner sides of the plates A' which plates are angled to form a track-way for the pulley stiles to slide upon and these spring clips also serve to secure the stiles in place while being operated upon.

50 The operation of the device is as follows:— The stiles M being placed and locked in position the lever D is brought into position shown in Fig. 1 thus bringing the circular saws in position to make the long cuts. The 55 saws are driven through the medium of the pulleys, shafts and belts already described and by rotating the handle K³ the stile is fed the desired length and at the desired speed. When the pin D⁶ strikes the end of the grip 60 D³ the saw E has finished its cut, and the grip is pressed to the handle D² releasing the pin D⁶. The lever D is then shifted, to throw the pulley stiles into engagement with the cross-cut saws and the operation is com-

pleted. By shifting the lever D inwardly the 65 two inner cross-cut saws J⁵ of each of the inner arms perform their cutting operation upon the inner sides of both the stiles at the same time. Upon shifting of the lever D to its outermost position the stiles are brought 70 into engagement with the four outer cross-cut saws all of which operate upon the outer sides of the stiles simultaneously thus finishing the operation by three movements, first, the feeding of the stiles longitudinally 75 by rotation of the shoulder K², the bringing them into engagement with the inner cross-cut saws and lastly by throwing them into engagement with the four outer saws, the last two movements being accomplished by 80 proper manipulation of the lever.

In the machine now in use the circular saw is ten inches in diameter and the inner cross cut saws are six inches in length, thus allowing two inches at each end of the inner 85 saws for the operation above described.

Having thus fully described my invention, what I claim as new and desire to secure by Letters Patent, is:—

1. A device of the kind described comprising a supporting table, a frame movable longitudinally thereupon, means carried by the frame for holding a pair of pulley stiles, circular saws adapted to operate upon both of the stiles at the same time, a plurality of 95 cross-cut saws, and means for successively bringing the inner and outer faces of the pulley stiles into engagement with the cross-cut saws.

2. A machine of the kind described comprising a longitudinally movable frame, horizontally arranged circular saws fixed with respect to said frame, means for feeding the frame, means for clamping pulley stiles upon 100 said frame upon opposite sides of the saws and in engagement therewith, a plurality of reciprocating cross-cut saws, adapted to engage the inner faces of the pulley stiles, a plurality of cross-cut saws adapted to engage the outer faces of the stiles and means 105 for bringing the stiles into engagement with each set of cross-cut saws.

3. A machine of the kind described comprising a movable frame, means for holding pulley stiles thereon, means for feeding the 115 frame, saws adapted to engage the pulley stiles and make the long cuts for pockets, fixed reciprocating cross-cut saws reciprocating cross-cut saws adjustably mounted with respect to the saws first mentioned, and 120 means for bringing the pulley stiles into engagement with said reciprocating saws for the end cuts.

4. A machine of the kind described comprising a table a frame movable thereon, 125 plates vertically mounted upon said frame, levers pivotally connected to said frame, rods secured to the plates and pivotally con-

nected to the levers, thereby bringing said plates into proper position, means for clamping a pulley stile to each plate, circular saws arranged between the plates, each saw operating simultaneously upon both of the pulley stiles, cross-cut saws arranged between said plates, means for reciprocating said saws, cross-cut saws arranged upon the outer sides of said plates, the said plates being cut out in alinement with the cross-cut saws, and adjusting means for regulating the cut of the cross saws.

5. A device of the kind described comprising holding means for a pair of pulley stiles, said holding means comprising two parallel plates, circular saws arranged between the plates and adapted to simultaneously produce the long cuts in both of the pulley stiles, reciprocating cross-cut saws working between the plates and making the cross-cuts simultaneously in each of said pulley stiles, and means for adjusting the distance between the plates to bring the

stiles into engagement with the cross-cut saws after the long cuts have been produced. 25

6. A device of the kind described comprising a table, a frame movable upon the table, a vertical shaft, said shaft being journaled in the table and projecting upwardly into the frame, parallel plates carried by the frame, and on opposite sides of said shaft, means for clamping pulley stiles thereto, circular saws carried by said shaft in position to engage two of the stiles at the same time, a horizontal shaft mounted in fixed bearings, 30 adjustable bearings, a shaft mounted horizontally in said adjustable bearings, reciprocating arms operable from said shaft, cross-cut saws carried by said arms and means for bringing the pulley stiles into engagement 35 with the cross-cut saws, as and for the purpose set forth.
